(57) **CLAIM**

The ornamental design for a media enclosure, as shown and described.

DESCRIPTION

FIG. 1 is a front perspective view of a media enclosure; FIG. 2 is a front elevation view of the media enclosure of FIG. 1; FIG. 3 is a rear elevation view of the media enclosure of FIG. 1; FIG. 4 is a right-side elevation view of the media enclosure of FIG. 1; FIG. 5 is a left-side elevation view of the media enclosure of FIG. 1; FIG. 6 is a top view of the media enclosure of FIG. 1; and, FIG. 7 is a bottom view of the media enclosure of FIG. 1. The broken lines depict portions of the media enclosure in which the design is embodied that are not considered part of the claimed design.
